UNITED STATES PATENT OFFICE

EUGENIO GALIZI, DECEASED, LATE OF BROOKLYN, NEW YORK, BY MARIA GALIZI, EXECUTRIX, OF BROOKLYN, NEW YORK, ASSIGNOR OF ONE-HALF TO ADRIANO GALIZI, OF NEW YORK, N. Y.

ACCORDION ILLUMINATING MEANS

Application filed April 17, 1931. Serial No. 530,907.

This invention relates to accordions and it pertains in particular to means illuminating an accordion.

One of the objects of this invention is to provide an illumination of the key board, illuminating means for that purpose being self-containedly incorporated in the accordion.

Another object of this invention is to provide means for distributing the light of said illuminating means over the whole length of the accordion, parts of the accordion serving as reflectors.

Another object of this invention is to arrange illuminating means on an accordion in such a manner that they enhance the effect of decorative parts of the accordion.

Another object of this invention is to provide on an accordion illuminating means, the operation of which is a function of the operations of the pitch slide mechanism.

Another object of this invention is to provide signal means on an accordion which visually call the attention of the audience to a change of the pitch slide.

Another object of this invention is to provide means for illuminating an accordion which allow the operator to observe the operation of the keys.

The reed-board of an accordion is ordinarily protected by an open work cover which serves mechanically to protect the reed board and the levers operating the same but which permits the sound to travel freely from the reed board in an upward direction.

Another object of this invention is to provide means for the observation and means accentuating the observation of the pallet actuating arms through the reed board cover.

Another object of this invention is to provide illuminating means upon an accordion in such a position, that their light is diffused by said open work cover.

Another object of this invention is to provide illuminating means upon an accordion which are directly focused on the keys thereof and which, at the same time, provide indirect illumination upon the accordion.

Another object of this invention is to provide illuminating means upon an accordion

in such manner that the light is reflected by the pallet actuating arms, actuation of said arms causing fluctuations in the effect of the light of said illuminating means.

These and other objects led to the invention which is described in the following and illustrated by the accompanying drawings, in which,

Figure 1 shows a perspective top view of an accordion.

Figure 2 shows a sectional, partly sectioned rear view of the key board and of the reed board of an accordion.

Figure 3 shows a cross section of the parts located above the reed board of an accordion.

Figure 4 shows a sectional end view of the key board and reed board, the latter one being partly cut open.

Figure 5 illustrates the manner in which the pitch slide mechanism actuates the illuminating means of this invention.

Figure 6 shows a diagram of the electric circuit of the illuminating means.

Similar numerals refer to similar parts throughout the various views.

In front of the key board 11 of the accordion a ledge 12 extends along the whole range of said key board. The pitch slide actuating lever 13 is countersunk into and forms part of said front ledge and it is substantially in level with said front ledge when in its normal position of rest. A trimming 14 runs around the top side of the key board and of the reed board 15, said trimming concealing the upper edges of the ledge of the pitch slide actuating lever 13 and the hinge 16 by which said lever is fulcrumed on said ledge. The pitch slide actuating lever 13 is hinged onto the ledge 12 in a recessed part of said ledge, below the trimming 14 by the piano hinge 16. Whereas the pitch slide actuating lever 13 substantially registers with the ledge 12 at the front thereof and, below the trimming 14, on the top thereof, the rear 17 of the pitch slide actuating lever 13 extends for a short distance above the rear of the ledge 12 and a flange 18 rectangularly extends from the pitch slide actuating lever 13 over the back of the key board.

Below said flange 18 a connecting rod 19 is fulcrumed in hinge 20 onto the pitch slide 100

actuating lever and the free end of said rod is hinged at 21 onto the pitch slide actuating key 22 which is mounted below the cover 23 and which is adapted slidably to reciprocate 5 in a suitable recess of said cover 23.

The free ends 24 of the escape levers 25 tensionally rest against the key 22. The lower ends of said escape levers 25 are hinged upon a toggle lever 26 which is fulcrumed at 27 10 upon the back of the key board; between the forked ends 28 of toggle lever 26 extends a lug 29 of the pitch slide or of a slide which is operatively connected with the pitch slide, and which is adapted laterally to reciprocate. 15

The piano hinge 16, in the manner of spring hinges, includes tension means which normally press the pitch slide actuating lever 13 frontwardly into alignment with the ledge 12. A stop 54 is provided on sliding key 22 which 20 prevents the pitch slide actuating lever 13 from swinging frontward beyond the level of the front of the ledge 12.

The force of the tension means which tend to open the hinge 16 is such that the pressure, with which the hand of the operator of the accordion normally rests upon the ledge while playing the instrument, does not push the lever out of alignment with the ledge 12. But conscious application of pressure by the 30 palm or otherwise will swing the back of the lever 16 into the corresponding recess in the ledge.

Each time the operator actuates the pitch slide actuating lever 13 by pressing down the 35 lower part thereof into a recess in the ledge 12, the slide key 22 engages upon one or the other of the escape levers 25, thus alternatingly swinging the toggle lever 26 in clockwise or counterclockwise direction, the forked ends 28 of said toggle lever reciprocating between the position to the left, in which they are shown, and a corresponding position to the right.

The toggle lever 26, as it is shown swung 40 to the left in clockwise direction, holds the pitch slide laterally in a position in which the pitch valves are open so that the octaves or harmonics controlled thereby are in an operable position. If the operator now depresses the pitch slide actuating lever 13, the toggle 45 lever is swung in counterclockwise direction to a position to the right and the pitch valves are closed by the pitch slide. Another operation of the lever 13 will return the pitch 50 slide to a position at which the pitch valves are open.

Upon the rear wall 30 of the reed board 15 is raisedly mounted a spring 31 which comes into electrical contact with toggle lever 26 55 when said toggle lever is swung to the right, said contact being interrupted when the toggle lever is swung to the left. The spring 31 is connected by an electric conductor 32 to a clamp 33, by means of which the shell 34 of the electric battery is mounted upon the wall.

30 of the reed board. Said battery is arranged in the reed box 35, so as to clear all reeds 36; insulating means 37, made of felt or other protecting material, are mounted next to the reeds upon the respective valves, to prevent injury to the reeds by the battery. The battery shell 34 contains one or more dry cell sections which are retained in the shell 34 by the pressure of a spring 38; that coiled spring 70 arises from the bottom of the plug 39, which is removably retained in one of the side walls of the reed boxes in a threaded opening 40. The dry cells may be removed from the battery shell 34 as soon as the plug 39 is removed, the threaded opening 40 being in alignment 75 with the battery shell 34. One pole of the battery connects to the conductor 32 by means of the clamp 33 which holds the shell 34. The other terminal of the dry cells is pressed by the tension of spring 38 against contactor 41, which arises from the back wall of the reed board and which connects to the electric conductor 42. 80

The cover 23 is connected by a conductor 43 to a toggle switch 44 and said switch is connected by the conductor 45, which together with conductor 42 extends through an opening 46 in the back wall of the reed board, to the electric light socket 47. The socket is supported above the reed board 15 and below the cover 48 by means of a bent-wire bracket 49. The electric light socket 47 holds an electric bulb 50 which is adapted to be lit by the current of the dry cells. Said bulb is located below an opening 51 in the cover 48 and a lens 52 is raisedly mounted in the opening 51; said lens serves to distribute the light radiated by bulb 50 above the cover 48. The electric light socket is mounted above the reed board substantially in level with the pallet actuating arms 53 which extend from the keys of the key board to the valves. The pallet actuating arms are ordinarily made of aluminum tubing or other shining metal so that the light of the bulb 50 which radiates towards both sides below the cover 48, is reflected by the bright metal of the pallet actuating arms 53 and is reflected through the openings, open work, metallic decorations, or protective and supporting 95 gauze of the cover 48. When the pallet actuating arms 53 are actuated by the keys of the key board, a change in the effect of the light of the bulb 50, as reflected by said pallet actuating arms is brought about, which draws 100 the attention of the audience to said pallet actuating arms and the respective keys so that the playing of the accordion may be followed by observation of the light reflected 105 through the cover 48.

At the same time the light of bulb 50 is reflected through the open parts of the cover 48 directly, thus increasing the pleasing effect of the arrangement and of the design 110 of the cover.

It is customary to perforate and decorate the cover 48 in an elaborate, flashy manner. It must permit free passage of the sound; at the same time the cover must protect the acoustic mechanism against foreign matter. Hence the cover 48 is composed of a perforated top plate 55 and a screen 56 in back thereof. The strands of the mesh of the screen 56 additionally intercept and to reflect the light radiating from bulb 50, whereby the quantity of light reflected through the cover is effectively increased. This aids the effect obtained from the arrangement of the bulb at the level chosen, since it is important to use the light most effectively, because, on account of the limited space in the accordion, a moderately sized current source is used.

Corresponding to the manner in which one light is arranged upon the accordion as illustrated in the drawings, two or more lights may be correspondingly distributed below the cover 48 and a variety of light effects may thus be produced.

These light effects are set into operation or shut off by the operation of the pitch slide actuating lever 13. As described and shown in the drawings, the pitch slide lever will turn on the light of bulb 50, when the pitch slide valves are closed and there is no light when the pitch slide valves are open. The main switch 44 allows the light to be shut off by separate control, so that the light of the bulb 50 may be shut off, even when the pitch slide is in a position of closing the pitch valves.

Although one form of the embodiment of the invention has been shown and described in detail, yet this patent is not to be limited thereby, except as the state of the art and the appended claims may require, for it is obvious that various modifications and changes may

be made in the form of embodiment of this invention, without departing from the spirit and scope thereof.

This invention is claimed, as follows:

1. In an accordion, pallet actuating means arranged upon a reed board, a transparent reed board cover, and an electric circuit including illuminating means arranged below said transparent reed board cover and above said pallet actuating means. 70

2. In an accordion, pallet actuating means arranged upon a reed board, a transparent reed board cover, and an electric circuit including illuminating means arranged centrally below said transparent reed board cover and above said pallet actuating means. 75

3. In an accordion, pallet actuating means arranged upon a reed board, a transparent reed board cover, and an electric circuit including illuminating means arranged below 85 said transparent reed board cover and above said pallet actuating means, and diffusing means projecting above said cover and registering with said illuminating means.

4. In combination with an accordion, a key board, a reed board cover confronting said key board at an obtuse angle, means illuminating said reed board cover, and means diffusing said illuminating means through said reed board cover onto said key board. 90

5. In combination with an accordion, a key board, a reed board cover confronting said key board at an obtuse angle, a source of electric current, lighting means operated by said source of current and illuminating 100 said reed board cover, and means diffusing said illuminating means through said reed board cover onto said key board.
